UNITED STATES PATENT OFFICE.

FREAS B. KLEINTOB, OF PHILADELPHIA, PENNSYLVANIA.

TABLE.

1,073,910.

Specification of Letters Patent. Patented Sept. 23, 1913.

Application filed November 25, 1912. Serial No. 733,457.

To all whom it may concern:

Be it known that I, FREAS B. KLEINTOB, a citizen of the United States, residing at Philadelphia, in the county of Philadelphia and State of Pennsylvania, have invented certain new and useful Improvements in Tables, of which the following is a specification, reference being had to the accompanying drawings.

10 This invention comprehends certain new and useful improvements in tables and relates more particularly to those which are adapted to be secured to chairs, beds or similar objects.

15 The primary object of the invention is to provide a table of this nature which shall be very simple in construction, cheap to manufacture and which, when not in use, may be disposed by the side of its support, so that it 20 will not be in the way.

A further object of the invention is to provide a table particularly adapted for use on arm chairs, and which may be vertically, angularly, or horizontally adjusted.

25 The invention also aims to generally improve devices of this nature and to render them more useful to students, invalids, doctors, etc.

With these and other objects in view, as 30 will become more apparent as the description proceeds, the invention consists of certain novel features of construction, combination and arrangement of parts as I shall hereinafter fully describe and claim.

35 For a complete understanding of my invention, reference is to be had to the following description and accompanying drawings wherein I have shown my invention in use on an arm chair and wherein—

40 Figure 1 is a side elevation of a chair showing my invention applied thereto, the dotted lines showing the position of the table when not in use. Fig. 2 is a front elevation. Fig. 3 is a side elevation of one of 45 the arms which support the table, together with the attachments thereto. Fig. 4 is a longitudinal sectional view through one of the table arms and the connections therewith. Figs. 5, 6, 7 and 8 are detail views 50 of parts of my invention which will be hereinafter more fully described.

Similar parts will be referred to in the following description and designated in the accompanying drawings by like reference 55 characters.

A designates an arm chair having the arms

B and rockers C. To the under side of each of the arms B a longitudinally extending rod 1 is connected by means of suitable brackets 2. Telescoping rods 3 are pivotally connected at their lower ends to the rockers C and at their upper ends to the sleeve members 4, which are slidably mounted upon the rods 1 and which are formed with depending spaced ears 5 between which the upper reduced ends of the rods 3 are pivotally connected. Each of the sleeve members 4 is also provided with a set screw 6 whereby the members may be locked in any desired position.

70 A rectangular platform 7 forms the table proper and has secured to its under side, by any suitable means, a drawer 8. A pair of angular brackets 9 is secured to the under side of the platform 7 adjacent each end thereof and supports the bars 10 and 11. Each of these bars is formed at its ends with the longitudinally projecting lugs 12 which project through central openings formed in the brackets 9 and the bar 10 is 80 also provided intermediate its end with an apertured depending ear 13 having one side thereof provided with the teeth 14. The bar 11 is formed intermediate its ends with a depending ear 15 which is provided with 85 the longitudinally extending end opening recess 16, the purpose of which will be hereinafter explained.

85 A doubly curved arm 17 having the sleeve member 18 formed upon one end thereof and provided at its other end with the horizontally projected portion 19 is slidably mounted upon one of the rods 3. The horizontally projecting portion 19 of the arm 17 is rectangular in cross section for a portion of its length and has slidably mounted thereon the toothed disk 20. The extremity 21 of the arm 17 is of a reduced size, circular in cross section and adapted to project through the apertured ear 13. An expansive spiral 100 spring 23 holds the teeth of the disk 20 normally in engagement with the teeth 14 on the ear 13. 24 designates a nut which is threaded upon the end 21 and which prevents the ear 13 from becoming detached from the 105 arm 17. From the foregoing description it will be seen that the normal engagement of the toothed disk 20 with the ear 13 prevents the latter from turning about the circular portion of the arm 17 and the platform is 110 therefore held against angular movement. To provide for the disengagement of the

disk 20 from the ear 13, I provide a push rod 25 which may be reciprocated within a longitudinal opening formed in the end portion 19 of the arm 17. The inner end of the 5 push rod 25 is provided with a transversely extending bar 26 which works within the slot 27. The toothed face of the disk 20 is provided with grooves for the reception of the cross bar 26 whereby the latter does not 10 interfere with the meshing of the teeth upon the opposed faces of the disk and the ear 13. When it is desired to disengage the disk 20 from the ear 13, the rod 25 is forced inwardly causing the cross bar 26 to force 15 the disk 20 inwardly against the spring 23. An arm 28 having the sleeve member 29 formed on one end thereof is slidably mounted upon the other of the rods 3 and is provided at its upper end with the outwardly 20 projecting horizontal portion 30 upon the end of which a nut 31 may be threaded. The end portion 30 of the arm 28 engages the walls of the slot 16 formed in the ear 15 and supports one end of the platform 7. 25 A book guard 32, clearly shown in Fig. 2, and having the laterally projecting portions 33 is secured to the inner side edge of the platform 7 and serves to hold a book thereon when the platform is tipped at an angle to 30 the horizontal plane.

It is thought that the foregoing description will suffice to a clear understanding of the construction of my improved chair table, the operation of which is as follows:—To 35 change the table from its operative position as shown in Fig. 2 to its inoperative position as shown by the dotted lines in Fig. 1, the end of the platform 7 which carries the bar 11 is swung upwardly whereby the other 40 end of the platform assumes a pivotal movement about the transverse bar 10 and the under side of said platform is caused to engage the end of the push rod 25 thus releasing the disk 20 from engagement with 45 the ear 13. The ear 13 is now free to rotate about the circular portion 21 of the arm 17 and the platform 7 is swung rearwardly and downwardly into a horizontal position parallel with the side of the chair. The set 50 screw 34 which locks the arm 17 on one of the arms 3 is next loosened and the arm 17 lowered to any desired position and then swung forwardly so as to bring the end portion 19 parallel to the side of the chair 55 after which the set screw 34 is again tightened and the platform 7 swung inwardly against the chair. This last inward movement of the platform releases the push rod 25 whereby the disk 20 is forced outwardly 60 into engagement with the toothed ear 13. When in use, the table may be turned at any angle to the horizontal plane and may be also moved toward or away from the occupant of the chair.

65 It is to be understood that while I have

shown and described a preferred embodiment of my invention, I do not wish to be limited to this exact construction and arrangement of parts but may make such changes as fall within the scope and spirit 70 of the invention.

What I claim is:—

1. The combination with an arm chair having a vertical rod secured to one side thereof, of a table attachment comprising 75 a platform, a transverse bar rotatably secured under said platform adjacent one end thereof, a depending apertured ear formed on said bar and provided upon one face with teeth, an arm mounted upon said vertical rod and having a horizontally projecting end portion, said end portion being circular at its extremity, a toothed disk slidably mounted upon said end portion and adapted to engage said toothed ear whereby 80 the latter is held against rotation and means mounted within the extremity of said arm whereby the toothed disk may be released 85 from engagement with the ear.

2. A table attachment for arm chairs comprising a platform adapted to be positioned across the arms of the chair, spaced brackets secured to the under side of said platform adjacent one end thereof, a transverse bar rotatably secured at its ends to said 90 brackets, the bar being formed intermediate its ends with a depending toothed ear having a circular opening formed therein, a vertical arm adapted to be secured to one side of the chair and having a horizontally projecting end portion, said end portion being rectangular in cross section for a portion of its length and having its extremity circular in cross section, a toothed disk 95 slidably mounted upon the rectangular portion of said arm, means for holding said disk in its outermost position in engagement with the toothed ear which is supported upon the circular portion of said arm, means for holding said ear upon the arm, and means positioned within the extremity of 100 said arm and adapted to be engaged by the under side of the platform to release the toothed disk from engagement with the ear 105 whereby the latter may be free to rotate 110 upon said arm.

3. A table attachment for arm chairs comprising a platform adapted to be positioned across the arms of said chair, depending brackets secured to the under side of 115 said platform adjacent one end thereof, a transverse bar rotatably secured at its ends to said brackets and formed intermediate its ends with a depending ear having teeth formed upon one face thereof and provided with a transverse opening, a supporting arm adapted to be secured to one side of the chair and having a horizontally projecting upper end portion, said end portion being 120 rectangular in cross section for a portion 125

of its length and rounded adjacent its extremity, said rounded portion being adapted to project through the ear and support the same, a toothed disk slidably mounted upon 5 the rectangular portion of the end of said arm, means for holding said disk in engagement with said ear, the rectangular end portion of the arm being transversely slotted, a push rod working through a longitudinal 10 opening in the extremity of the arm and provided upon its inner end with a cross bar for engagement with the toothed disk whereby the latter may be disengaged from said ear, and means securing said ear 15 upon the arm.

4. The combination with a rocking chair having arms, of longitudinally extending rods secured to the under side of said arms, vertical telescoping rods pivotally secured at 20 their lower ends to the rockers of the chair and slidably connected at their upper ends to said first mentioned rods, a platform having a pair of depending brackets pivotally secured to the under side thereof adjacent 25 each end, transverse bars rotatably secured at their ends to said brackets and provided intermediate their ends with depending ears, one of said ears being toothed, a connecting arm slidably mounted upon one of said 30 telescoping rods and having a horizontally projecting end portion rectangular in cross section for a portion of its length and having its extremity reduced in size and circular in cross section, said circular portion projecting through the toothed ear and supporting the same, a toothed disk slidably mounted upon the rectangular portion of said bar and adapted to engage the ear to prevent rotation thereof, said rectangular portion being 35 transversely slotted, a push rod projecting longitudinally through the reduced circular portion of said arm and provided upon its extremity with a transverse bar working within said slot, the outer end of 40 the push rod being adapted to be engaged by the under side of said platform whereby the toothed disk is forced inwardly, means for normally holding said disk in its outermost position, a nut threaded upon the end 45 of said arm and a second arm slidably mounted upon the other telescoping rod and having a laterally projecting end portion adapted to be engaged by the other of said 50 ears.

5. A table attachment for arm chairs comprising a platform arranged across the arms of the chair, longitudinally extending rods secured to the under side of said arms, vertical telescoping rods pivotally secured at their lower ends to the rockers of the chair 60 and slidably connected at their upper ends to said first mentioned rods, an arm connected at one end to one of said vertical rods, said arm being pivotally connected at its opposite end to the under face of said platform near one end thereof, whereby said platform may be adjusted angularly and horizontally with relation to the arms of 65 said chair, as and for the purpose described.

6. A table attachment for arm chairs comprising a platform arranged across the arms of the chair, a bar rotatably mounted upon the under face of said platform near one end thereof, a depending apertured ear formed on said bar, a vertical rod secured at 70 one side of said chair, an arm mounted at one end upon said vertical rod, the opposite end of said arm projecting through said apertured ear and rotatably supporting the same, a disk slidably mounted upon said opposite end of the arm and adapted to engage 75 said apertured ear, said disk and ear being formed on their opposing faces with teeth, and means adapted to release said toothed disk from engagement with the said toothed 80 ear, as and for the purpose described.

7. The combination with an arm chair having a vertical telescoping rod arranged at one side thereof, of a table attachment comprising a platform arranged across the 90 arms of the chair, a rod secured to the under face of one of the arms of the chair and extending longitudinally thereof, said vertical rod being pivotally secured to one of the rockers of said chair at its lower end, the 95 upper end of said rod being slidably connected to said longitudinally extending rod, and an arm slidably mounted at one end on said vertical rod, the opposite end of said arm being pivotally secured to the under 100 side of said platform adjacent one end thereof, as and for the purpose described.

In testimony whereof I hereunto affix my signature in the presence of two witnesses.
